UNITED STATES PATENT OFFICE.

JAMES R. DAIL, OF GOLDSBORO, NORTH CAROLINA.

TRUSS.

1,147,379.

Specification of Letters Patent. Patented July 20, 1915.

Application filed May 6, 1913. Serial No. 765,876.

To all whom it may concern:

Be it known that I, JAMES R. DAIL, citizen of the United States, residing at Goldsboro, in the county of Wayne and State of North Carolina, have invented certain new and useful Improvements in Trusses, of which the following is a specification.

This invention relates to trusses and it has as its primary aim to provide a surgical appliance of this class which will be entirely comfortable to the wearer and will properly support a rupture or other abdominal disorder, and be not liable to slip or yield so as to cause discomfort.

Another aim of the invention is to provide a truss of such construction that it will not exert undue pressure against the wearer's back and will have no metal parts liable to come into contact with the body.

The invention has as a further object the provision of a simple adjusting means for the crotch straps which means will not be liable to become disarranged by the wearer's clothing.

In the accompanying drawings: Figure 1 is a perspective view of the truss applied; Fig. 2 is a view partly in section and partly in plan, parts also being broken away, illustrating the waist encircling portion and the pads of the truss; Fig. 3 is a vertical sectional view on the line 3—3 of Fig. 2; Fig. 4 is a vertical sectional view illustrating the adjusting means for the crotch straps; Fig. 5 is a perspective view of one of the hooks 35 for holding the crotch straps at adjustment.

Corresponding and like parts are referred to in the following description and indicated in all the views of the accompanying drawings by the same reference characters.

In the drawings the numeral 1 indicates the waist band of the truss which may be of any suitable material and which is designed to encircle the waist of the wearer at the front and above the hips but which is open 40 at the back. Connected to one end of the waist belt 1 is a strap 2 and a similar strap 3 is connected to the other end of the belt. These straps are, in applying the truss, crossed upon the wearer's back at a point 45 slightly above the waist line and then pass around the trunk and in front of the shoulders, the strap 2 being led over one shoulder and in back of the wearer's neck and adjustably connected with the strap 3 either 50 by means of a hook 4 and openings 5 respectively upon and in the straps 3 and 2, or by

any ordinary buckle or other fastening device which will hold the straps connected at adjustment.

The pads of the truss are indicated in 60 general by the reference numeral 6 and the pads are preferably stuffed and may be of leather, cloth or any other suitable material and each pad has a rear portion 7 and a forward portion 8 which are connected by 65 seams 9 at the sides.

The forward portion of the waist belt 1 constitutes a portion of the front 8 of each pad at the upper end thereof as clearly shown in Fig. 3 and as indicated at 10, 70 although if desired the said front portion may extend the entire height of each pad and the waist belt may be attached to the pads in any suitable manner.

In order that the pads may fit the body in 75 such a manner as to fit the pubic bone a line of stitching indicated at 11 is run transversely across each pad at a point approximately between the upper and lower ends thereof so that each pad is contracted 80 between its side ends. The pads may be stuffed with cotton or any suitable material 12 and they are preferably located one at each side of the middle of the waist belt 1. It is also preferable that the pads be of 85 greater thickness than width at their upper portion and that they taper slightly in the direction of their lower ends, and attached to each pad at its lower end is the forward 90 end of a crotch strap 13. The crotch straps 13, in applying the truss, are passed about the thighs and the rear ends of the straps are then adjustably connected with the waist belt 1 near the ends of the latter in a manner 95 now to be explained.

In providing a connection between the rear ends of the crotch straps and the corresponding ends of the waist belt 1, I make use of suspension hooks each of which is formed from a single length of wire bent upon itself 100 as at 14, the wire being then bent as at 15 so as to form a hook the bill of which is indicated at 16. The portions of the wire at the other side of the bend 15 constitute the shank of the hook and this shank is held between the waist belt 1 and the pocket straps 17 which are stitched to said waist belt. The wire at the upper end of the shank of each hook is bent laterally in opposite directions as indicated at 18 and these portions are 110 also housed between the waist belt 1 and the pocket strap 17, stitches 19 being run

through the said belt and strap beneath the portions 18 hereby to provide for a firm support for the hooks. Attached to the crotch straps 13 are relatively short straps 20 which may be of any suitable material, although preferably of leather and these straps 20 are provided each with a number of openings 21 designed to receive the bill of the respective hook.

- 10 From the foregoing description of the invention it will be seen that the truss may be readily and quickly applied and adjusted and that the straps 2 and 3 are adapted to support the rear side of the belt 1 and not for
- 15 the entire belt, at the desired point upon the body of the wearer, the crotch straps being adjustable to more or less firmly bind the pads of the truss against the part to be supported. It will further be apparent that the
- 20 pads may be adjusted to bear more or less firmly against the abdomen.

Having thus described the invention, what is claimed as new is:

1. In a truss, a waist-belt having its rear ends spaced apart, spaced depending pads carried at the front of the belt and secured thereto upon each side of a point midway between the ends of the belt, a crotch strap secured at one extremity to each of said pads
- 25 and having its opposite extremity free, an adjustable connection between the free extremity of each of said straps and the ad-
- 30

jacent extremity of the belt, said straps being connected with the belt adjacent the ends thereof, and adjustably connected coacting straps secured to the ends of the belt and disposed to cross each other upon the back of the wearer.

2. In a truss, a waist-belt having its rear ends spaced apart, spaced depending pads 40 carried at the front of the belt and secured thereto upon each side of a point midway between the ends of the belt, a crotch strap secured at one extremity to each of said pads 45 and having its opposite extremity free, an adjustable connection between the free extremity of each of said straps and the adjacent extremity of the belt, said straps being connected with the belt adjacent the ends thereof, and adjustable coacting straps secured to the ends of the belt and disposed to cross each other upon the back of the wearer, 50 one of said last mentioned straps being relatively longer than the other to extend partially around the trunk, beneath one arm, 55 over the adjacent shoulder and in the rear of the neck to engage the other strap in the front of the opposite shoulder.

In testimony whereof I affix my signature in presence of two witnesses.

JAMES R. DAIL. [L.S.]
